UNITED STATES PATENT OFFICE.

JAMES THORN GOODFELLOW, OF HUNTINGDON, PENNSYLVANIA, ASSIGNOR
TO THE IRON CAR COMPANY, OF CONNECTICUT.

END SILL FOR RAILWAY-CARS.

SPECIFICATION forming part of Letters Patent No. 400,329, dated March 26, 1889.

Application filed August 16, 1888. Serial No. 282,837. (No model.)

To all whom it may concern:

Be it known that I, JAMES THORN GOODFELLOW, of Huntingdon, in the county of Huntingdon and State of Pennsylvania, have 5 invented an Improvement in End Sills for Railroad-Car Bodies, and the following is declared to be a description of the same.

Various forms of end sills have heretofore been made, and improvements in such end 10 sills have been secured to me by Letters Patent, as follows: Dated June 26, 1888, No. 385,177; and my present invention relates to an end sill of peculiar and novel construction, the details of which are hereinafter set 15 forth.

My improved end sill is constructed of horizontal plates, to which are connected end caps and central sills, and said end caps and central sills are adapted to receive and be 20 connected to the longitudinal tubes forming the frame of the car, and between said horizontal plates there are X-shaped struts or frames, and connected to said horizontal plates and central sills there are buffers of 25 usual construction, and said plates are bent or bow-shaped, and there are links which pass at one side of the central sills, and whose ends are fastened in the end caps, these links forming a bow in the opposite direction to that 30 of the horizontal plates and assisting with the other parts, all of which are rigidly bolted together to form a very compact and rigid end sill for a car-body.

In the drawings, Figure 1 is a plan view of 35 my improved end sill. Fig. 2 is an elevation of the front or face of the sill. Fig. 3 is an elevation of the back of the sill. Fig. 4 is a cross-section at the line xx of Fig. 2, and Fig. 5 represents the parts shown in Fig. 4 40 as separate from each other. Fig. 6 is a cross-section at the line yy of Fig. 2, and Fig. 7 shows the parts of Fig. 6 separately. Fig. 8 is a section at the line zz , and Fig. 9 is a view of the parts of Fig. 8 separately. Fig. 45 10 is a section at the line vv , and Fig. 11 is a view of the parts of Fig. 10 separately. Fig. 12 is a section at the line ww , and Fig. 13 shows the parts separately. Fig. 14 is a cross-section at the line uu . Fig. 15 is a cross- 50 section at the line tt , and Fig. 16 shows the

end cap of the sill by face and rear perspective views.

My improved end sill is constructed of the following parts: The horizontal plate a is bent of a bow shape (see Fig. 1) and extends along the upper edge of the end sill. The horizontal or bottom plate, b , is similarly shaped, and is also bowed downwardly at its central portion, b' , and there is an auxiliary bowed plate, b^2 , which is of short length and is riveted to the plate b at its ends, as shown in Fig. 2, and there are malleable cast-metal bracket-pieces c , bolted together at 1 and extending across and engaging the edges of the bowed plates $b' b^2$, and there are supports c' 65 between the upper edge of said bracket-pieces c and the under edge of the plate a , and the bolts at 2 connect the parts together. The space formed between the bracket-pieces c and the bowed plates $b' b^2$ is adapted to receive the draw-bar of usual construction. 70

At each side of the center of the end sill there are face-caps or central plates at d , and these face-plates are adapted to receive the buffers e , and said face-plates are securely 75 bolted at 3 4 to the top and bottom plates, a b , and at 5 6 by bolts which pass through said plates and between the plates $a b$ and through the central sills, ff' , and are connected to heads which secure the longitudinal tubes of 80 the car-frame in a manner similar to that heretofore described by me in my Letters Patent No. 385,177.

The central sills, ff' , are formed in two pieces, as shown in Fig. 11, which pieces abut 85 against each other and are secured against the inner edges of the top and bottom plates, $a b$, by said bolts 5 6, and there are bolts 7 8, which also pass through said central sills, ff' , and serve to hold the buffers e in place 90 against the face of the plates d ; and at g , I have shown frames for supporting the vertical brake-rod g' of the car. The end caps consist of the parts $h i$, which parts have projecting flanges $h' i'$, adapted to set against 95 the edges of the top and bottom plates, $a b$, at the respective ends of the sill, and there are bolts 9 10, which pass through and connect these flanges together. The longitudinal tubes k are adapted to be received in 100

the end caps, *i*, and the same are secured to said end caps by headed bolts in a manner similar to that set forth in my patent aforesaid, and these bolts *l* not only serve to hold the tubes *k* to the end caps, *i*, but to clamp the end caps, *i* and *h*, together.

At each end of the end sill, between the plates *d* and the end caps, *h i*, there are head-blocks *m m'* between the top and bottom frames, *a b*, and said head-blocks are bolted at regular distances apart to the plates *a b*, and between said head-blocks there are **X**-shaped struts or frames *n*, and these parts serve as a stiffening to the end sill, and act 5 to prevent the same sagging in any respect.

The link-brace is composed of the central link, *o*, and the end links, *r s*, this central link, *o*, being between the longitudinal tubes *k'* and the links *r s*, engaging with the link *o*, and passing around at the back of the central sills, *f'*, and the respective ends of the links *r s* pass through the end caps, *h*, and have nuts on their ends by which they are held in place, said links *o r*, and *s* forming a 5 brace or bow in a direction or shape the opposite of that which is given to the top and bottom plates, *a b*, said links acting to tighten and strain, as well as to stiffen, the frame forming the end sill of the car.

The various parts of my improved end sill are preferably made of malleable cast metal, and when connected together in the manner described form a very solid and rigid end sill, and should any one or more pieces get broken or damaged, in case of a collision, it becomes an easy matter, comparatively speaking, to remove those parts and to insert in their place parts that are interchangeable.

I claim as my invention—

1. An end sill for railroad-car bodies composed of two or more horizontal bent plates, *a b*, the face-plate *d*, the central sills, *f f'*, the end caps, *h i*, and bolts for connecting the respective parts together, and the brace system of links *o r*, and *s*, substantially as set forth. 45

2. The combination, with the horizontal plate *a*, of the plate *b*, having a bowed portion, *b'*, the bowed plate *b'*, and the bracket-piece *c* and supports *c'*, substantially as set forth. 50

3. The combination, with the horizontal top and bottom plates, *a b*, of the central sills, *f f'*, connected therewith and adapted to receive longitudinal tubes, and the end caps *h*, connected to the end caps *i*, and bolts for securing the said parts to the top and bottom plates, substantially as set forth. 55

4. The combination, with the horizontal top and bottom plates, *a b*, of the head-blocks *m m'* and bolts for connecting said head-blocks 60 to said plates, and the **X**-shaped studs or frames *n*, adapted to be received between the plates *a b* and the blocks *m m'*, substantially as set forth.

5. The combination, with the horizontal top and bottom plates, *a b*, and the end caps, *h i*, of the two-part central sills, *f f'*, and the bolts for connecting the same to the top and bottom plates, the link-brace system *o r*, and *s*, secured at its ends in the end caps, *h i*, and 70 passing behind and bearing upon the sills *f'*, substantially as and for the purposes set forth. 65

Signed by me this 1st day of August, 1888.

JAMES THORN GOODFELLOW.
